FRAME FOR A CLUB CHAIR

Maurice Martiné, Capistrano Beach, Calif., assignor to Ryder Elliott, Inc., Los Angeles, Calif., a corporation of California

Application November 1, 1956, Serial No. 43,637

Term of patent 3½ years

(Cl. D15—1)

The figure is a perspective view of a frame for a club chair, showing my new design.

I claim:

The ornamental design for a frame for a club chair, substantially as shown.
